UNITED STATES PATENT OFFICE.

JOSEPH C. BIANCA, JR., OF SCRANTON, PENNSYLVANIA.

MORTISING MACHINE.

Application filed October 2, 1924. Serial No. 741,238.

This invention has reference to woodworking machines and more particularly to a machine for mortising doors or the like, the primary object of the invention being to provide a device of this character which will facilitate the operation of providing a mortise and one wherein the mortise when completed will be true and accurate.

An important object of the invention is to provide a device of this character which may be adjusted to adapt the device for use in forming mortises of various widths and lengths.

A still further object of the invention is to provide a machine of this character which may be readily and easily clamped to the door or article under operation.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a mortising machine constructed in accordance with the invention, and showing the same as clamped to a door.

Figure 2 is a side elevational view thereof.

Figure 3 is a plan view of the central supporting beam of the machine.

Figure 4 is a sectional view taken on line 4-4 of Figure 1.

Figure 5 is a perspective view of the frame of the machine.

Figure 6 is a perspective view of the central supporting beam.

Figure 7 is a sectional view taken on line 7-7 of Figure 2.

Figure 8 is a sectional view taken on line 8-8 of Figure 2.

Figure 9 is a perspective view of the U-shaped bracing member.

Figure 10 is a perspective view of one of the nuts through which the feed screws move.

Figure 11 is a perspective view disclosing the members that hold the sprocket supporting arms in their positions of adjustment.

Referring to the drawings in detail, the frame of the machine is indicated generally by the reference character 5 and includes an

upper removable section 6 formed with cut out portions 7 that register with cut out portions 8 at the opposite side of the frame for the reception of the nuts 9. These nuts 9 are formed with cut out portions 10 defining shoulders to engage the inner surfaces of the frame to restrict movement of the nuts with respect to the frame. As shown, the upper removable section 6 is secured to the lower portion of the frame by means of the bolts 11.

Spaced arms 12 are formed integral with the lower section of the frame and extend forwardly where they are provided with threaded members 13 through which the screws 14 move, the forward ends of the screws being provided with clamping members 15 that are designed to clamp the opposite sides of a door to hold the machine to its work.

A U-shaped bracing frame 16 is secured to the under surfaces of the arms 12 by means of the screws 17 that pass through threaded openings in the right angled portion 18 of the U-shaped bracing frame.

Adjustably supported by the U-shaped bracing frame is a plate 19 formed with an elongated opening 20 that receives the screw 21 by means of which the plates 19 may be adjusted with respect to one edge of the mortise to be cut, so that the material adjacent to the edge of the mortise will not split while the blades are passing through the material.

As clearly illustrated by Figure 5 of the drawings, the supporting frame is provided with offset portions 22 which provide guides for the central supporting beam 23 which moves through the guides and operates longitudinally of the main frame.

The supporting beam 23 is formed with a central rib that has its ends disposed in spaced relation with the ends of the supporting beam proper to provide a space for the sprocket supporting arms 24 that are formed with openings to accommodate the securing pin 25 that passes through the opening 26 formed in the supporting beam 23. These arms 24 are curved so that they will extend laterally and as shown, the arms support sprockets 28 over which the endless cutting member, to be hereinafter more fully described, moves. In order that the arms 24 may be held in proper spaced relation with each other spacing members 29 are provided, there being a spacing member carried by

each arm. Each spacing member is formed with a cut away portion providing a shoulder 30 which shoulder is adapted to engage the opposite arm and restrict movement of the arms with respect to each other, a suitable securing pin being provided for holding the spacing members to their opposed arms. Securing screws 31 hold the members 29 to the supporting arms and it will be obvious that should it be desired to move the arms 24 greater distances apart, it is only necessary to remove the members 29 and replace them with longer spacing members wherein the shoulders fall to such positions that they will cause the outer ends of the arms 24 to be held greater distances apart.

Secured to the supporting beam adjacent to one end thereof are angle irons 32 which are provided with openings in which the feed screws 33 move, the feed screws carrying pinions 34 at their outer ends, while the inner ends thereof move through the nuts 9 to cause the feed screws 32 and the supporting beam carried thereby to be fed longitudinally of the frame of the machine.

Positioned in the openings 35 formed adjacent to the outer end of the supporting beam are suitable bearings to accommodate the shaft 36 that carries pinions 37 meshing with the pinions 34 whereby rotary movement of the shaft 36 is imparted to the pinions 34 to rotate the feed screws 33 and accomplish the result as previously described.

Mounted on the shaft 36 is a main sprocket 38 over which the endless cutting member 39 moves, the endless cutting member being in the form of a chain and provided with a plurality of cutting blades 40 which are pivotally supported between the side members of the links of the chain. It might be further stated that it is contemplated to employ a quick-acting securing member for securing the ends of the chain,

so that should it be desired to remove the cutting members and replace them with cutting members for the cutting of a larger mortise, the cutting member on the machine may be removed and replaced with facility.

The shaft 36 is operated by means of the handle 41 so that the operator may by standing at the rear of the machine, rotate the sprocket wheel 38 for moving the endless cutter.

In order that the machine may be further steadied, a handle 42 is provided at the opposite side of the machine, and is designed to be gripped by the left-hand of the operator when the machine is in operation. From the foregoing it will be obvious that when the handle 41 is rotated, the shaft 36 is also rotated to move the sprocket 38 which in turn moves the endless cutter that passes over the sprocket 28 to the end that the endless cutting member is moved into engagement with the door being mortised, the cutting blades 40 moving through the material by the action of the feed screws 33.

I claim:

A portable mortising machine including a main frame, a supporting beam mounted on the frame and adapted to be moved longitudinally thereof, a pair of arms pivotally carried at one end of the beam, sprockets mounted on the free ends of the arms, a removable spacing member connected with each arm, each spacing member having a shoulder to engage the adjacent arm to hold the arms in spaced relation with each other, an endless cutting member operating over the sprocket wheels and adapted to urge the arms inwardly against the spacing members, and means for operating the cutting members.

In testimony that I claim the foregoing as my own, I have hereto affixed my signature.

JOSEPH C. BIANCA, JR.
